ROTARY REFINER

Edmund P. Arpin, Jr., Neenah, Wis.

Application November 7, 1952, Serial No. 319,293

3 Claims. (Cl. 92—26)

1

This invention relates to a material-treating machine and more particularly to improvements in rotary refining machines which are used to refine wet, fibrous material, such as pulp, paper stock and the like. The present invention especially has to do with improvements in the material-treating rotor assemblies.

It is an important object of the present invention to provide a rotary assembly for a refining machine or the like which will serve to control passage of material through the machine.

It is another object of the invention to provide an improved backing plate for rotary refiners and the like having novel means for controlling stock passage through the machine.

It is a further important object of this invention to provide a simpler and more economical construction which is also especially satisfactory in the refining of low consistency stock.

Other and further important objects of this invention will be apparent from the disclosures in the specification and the accompanying drawings.

On the drawings:

Figure 1 is a fragmentary cross-sectional view of a rotary refiner embodying the principles of my invention;

Figure 2 is a fragmentary front elevational view of a backing element of the rotary assembly of the rotary refiner of Figure 1; and

Figure 3 is a fragmentary transverse sectional view taken substantially along the line III—III of Figure 2.

As shown on the drawings:

In Figure 1, the reference numeral 10 indicates generally a rotary refiner embodying the principles of my invention, including a generally cylindrical shell or casing 11 provided with a liner 22 composed of a number of ring sections 23 which are formed of suitable abrasive material, such as stone, metal or a synthetic ceramic of an abrasive type. A series of equally spaced helical grooves 24 extend longitudinally in the machine and form continuous passages along the inner surface of the ring sections 23. The ring sections such as shown in Figure 1 at 23 are disposed in side-by-side relation along the length of the machine, and stock introduced at one end of the machine travels longitudinally through the machine over successive ring sections.

The particular refining machine herein illustrated includes rotor assemblies 25 pivotally mounted on a housing 26, in peripheral sets of four each, for rotation with the hollow shaft 19

2

to which a tubular central portion 33 is keyed. Each rotor assembly includes a refining element 27 secure in a backing plate 28 which has spaced upstanding ear portions 31, Figure 2, which straddle flange parts 32 on the housing 26 and are pivotally mounted thereon by a pin 30. As the shaft 19 is rotated, the rotors move outwardly by centrifugal force causing the refining element to coact with the abrasive surface of the liner ring 23 to refine the fibrous material as it is moved between the refining surfaces by the action of an impeller at the inlet end (not shown) and by the pressure head under which material is delivered to the inlet opening. Both the liner ring 23 and the refiner element 27 may be formed of stone, metal or of a synthetic ceramic of an abrasive type.

A positive acting linkage for maintaining a minimum clearance at all times between the surface of each refining element and the abrasive surface of the liner ring 23 comprises a lever 35 pivotally mounted on the pin 30 on which is journaled the refining element 25. The lever 35 at one end engages a bracket 39 carried by the refining element 25 and the other end is disposed in abutting contact with the end of a push rod 42 slidably mounted in aligned radial apertures in the hollow shaft 19 and the housing 26.

As a means of controlling the radially inward and outward movement of the push rod 42, there is provided a series of frusto-conical wedge members 43 secured to telescoping rods (not shown) extending longitudinally inside the shaft 19.

Further details of the construction and operation of a refining machine to which my novel rotor construction may be applied, may be found by reference to U. S. Patent No. 2,475,869 to Edmund P. Arpin, Jr., on an application Serial No. 640,734, filed January 12, 1946.

The backing plate 28 comprises a substantially flat central portion 52 with an overhanging ledge 53 which extends across the leading end of the plate forming a seal against which the corresponding portion of the stone 27 is pressed when the rotor is assembled therein. At both sides of the backing plate a wall portion 55 extends away from the flat central portion 52.

A metal pressure pad 59 is disposed across the trailing edge of the rotor stone with a pad of cushioning material between the surfaces of the pad 59 and the stone. This cushioning pad may be of a material such as rubber, soft metal alloy or plastic to protect the stone surface under compression against the metal surfaces. A se-

ries of wedges 62 are disposed between a marginal flange 63 at the trailing edge of the backing plate 28 and the pressure pads 59. Stud bolts 65 are threaded at one end into each backing plate 28 and at the other end pass freely through an opening in each wedge 62.

According to the present invention, for retarding passage of stock through the machine, a deflector or fin element 70 is disposed at the leading edge of each refiner element backing member 28. As best seen in Figure 2, the fin may be located toward the outlet side of the refining machine, so as to tend to trap stock in the path of the associated refiner element 25 during rotation of the rotor assembly. It will be observed, that the fin 70 tends to block the gap such as indicated at 71, Figure 1, between succeeding rotor elements 25, and thus to reduce the cross-section of the path available to the stock through the machine. It will be observed that the outer edge of fin 72 is illustrated as being generally parallel to the inner surface of the abrading ring 23 and in close proximity thereto for substantially blocking travel of stock through the machine immediately in front of the refiner element such as 27.

The fin 72 is positioned on each backing plate and purposely placed toward the outlet side of the machine so that as the stock flows through the machine in an axial direction, while hugging the surface of the abrasive liner 23 because of centrifugal force, the stock is partially trapped and deflected by the various fins into the converging space S between the leading surface of each refining element and the abrasive liner 23. In this way a greater amount of refining is accomplished for a given size of machine and speed of rotation of the refining element.

It will be understood that details of construction may be varied through a wide range without departing from the principles of the present invention, and it is, therefore, not the purpose to limit the patent granted hereon otherwise than necessitated by the scope of the appended claims.

I claim as my invention:

1. In a material-treating machine, a stationary

shell having a cylindrical abrasive liner, through which material flows axially from an inlet to an outlet end thereof, a rotatable shaft mounted within and axially of said shell, centrifugally acting rotor elements carried by said shaft and peripherally spaced within said shell and movable toward said abrasive liner, said rotor elements including a backing plate and a material-treating element carried by said backing plate for cooperation with said abrasive liner, and means carried at the leading end of said backing plate for retarding passage of material axially of the shell, and for deflective material between said element and said abrasive liner.

10 2. In a material-treating machine including rotor elements for moving transversely of the direction of passage of material through said machine and carrying a material-treating element for interaction with the material, the improvement which comprises a deflector member carried at the leading edge of said rotor elements for retarding the passage of material through said machine and deflecting said material into the path of movement of said rotor elements.

20 3. In a material-treating machine, a stationary shell having a cylindrical abrasive liner, through which material flows axially from an inlet to an outlet end thereof, a rotatable shaft mounted within and axially of said shell, centrifugally acting rotor elements carried by said shaft and peripherally spaced within said shell and movable toward said abrasive liner, said rotor elements including a backing plate and a material-treating element carried by said backing plate for cooperation with said abrasive liner, and means carried at the leading end of said backing plate for retarding passage of material axially of the shell, and for deflective material between said element and said abrasive liner, said retarding means comprising a fin projecting forwardly from the leading end of the backing plate to partially close the space between succeeding rotor elements.
